INFLATED GRINDING WHEEL

Arthur Raske, Willoughby, Ohio

Application October 2, 1956, Serial No. 613,574

4 Claims. (Cl. 51—192)

My invention relates to a new and useful improvement in an inflated grinding wheel so constructed and arranged that the supporting body of the wheel on which the abrasive material is to be mounted may be inflated so as to securely bind the circular band of abrasive material which embraces the same.

It is an object of the present invention to provide a grinding wheel of this class which will be simple in construction, economical of manufacture, durable, compact, easily and quickly assembled, and highly efficient in use.

Another object of the invention is to provide a grinding wheel of this class so constructed and arranged that improved concentricity at the periphery of the wheel is accomplished.

Another object of the invention is the provision of a wheel of this class so constructed and arranged that an improved air seal between the inflated body and the rigid core is accomplished so that the internal pressure applied through the air valve will force the inflated embracing member into proper relationship to the rigid core without additional processes.

Another object of the invention is the provision of a grinding wheel of this type so constructed that no axial pressures are exerted upon the core member.

Another object of the invention is the provision of a grinding wheel of this type having a rigid core member provided with inwardly directed threaded passages for reception of the valve stem, thus eliminating the necessity of a special valve housing.

Another object of the invention is the provision of a grinding wheel of this class so constructed and arranged that it may be economically manufactured due to the fact that the rigid core may remain constant for various diameters of inflated drums or parts.

Another object of the invention is to provision in a grinding wheel of this class of a drum or inflatable annular member so constructed and arranged that a stable balanced wheel will be provided and the drum or inflatable member will be prevented from flying off of the rigid core.

Other objects will appear hereinafter.

It is recognized that various modifications and changes may be made in the detail of structure illustrated without departing from the invention and it is intended that the present disclosure shall be considered to be but the preferred embodiment.

Forming a part of this application are drawings in which:

Fig. 1 is an end elevational view of the invention;

Fig. 2 is a sectional view taken on the line 2—2 of Fig. 1;

Fig. 3 is a fragmentary enlarged sectional view taken on the line 3—3 of Fig. 2, showing the valve in closed position;

Fig. 4 is a view similar to Fig. 3, but showing the valve in open position.

2

As shown in the drawings, the invention comprises a rigid core 7, made from any suitable material and preferably of metal. I have found that it is an advantage to construct this core from a light metal, such as aluminum. This core 7 has a threaded bore 8 formed therethrough extending from end to end. At the opposite ends of the core 7 is an inwardly directed flange 9 to provide a circular groove 10. The opposite end faces of the core are counter-bored inwardly as at 11. Formed in one of the end faces of the core 7, at the inwardly bored portion 11, is a threaded passage 12 in which is threaded a shell or housing 13, through which slidably projects a valve stem 14 carrying at its inner end the valve head 15 which, when the valve is in closed position, will engage against the end of the shell 13 and effect an air seal.

Embracing the stem 14 is a coil spring 16 which bears at one end against the reduced end of the shell 13 and at its opposite end against the collar 17 formed on the valve stem 14. The construction of this valve is similar to that used on vehicle tires and will sometimes be referred to herein as a tire valve. The shell 13 opens at its inner end into the passage 18 communicating with the lateral passage 19.

25 An inflatable drum is used with this mechanism and comprises an annular member having the periphery forming member 20 and the side walls 21 and 22 which are inclined to the periphery 20. Each of these side walls is provided with a head 23 embodying a flange 24 which is adapted to snugly engage in the groove 10. The inner face of this head engages firmly against the periphery 26 of the rigid core 7. It will be noted that this head extends outwardly of the flange 9 so as to fill the groove 10, and also extends inwardly from this flange a distance so that the heads on the opposite side walls 21 and 22 project inwardly toward each other but are spaced apart. At the space separating the opposed ends of this head, the passage 19 is located.

In use, the inflatable drum is embraced by an endless band 25 of suitable abrasive or grinding material. Air may be forced under pressure into the interior of the inflatable drum, through the valve, and through the passages 18 and 19, so as to force the periphery 20 of this inflatable drum outwardly into tight engagement with the encircling band 25 of abrasive material. The threaded bore 8 may be made a proper size for receiving a power spindle which will serve to rotate the grinding wheel when in use.

50 It will be noted that as the air is forced into the inflatable drum, the air pressure will move the various parts into assembled relation to the rigid core 7. Due to the large supporting area at the heads 23, the concentricity of the periphery 20 is improved.

55 Experience has shown that the core member is possessed of a greater life because there are no pressure exerting members directing the pressure axially of the core, as is common in inflatable grinding wheels.

Experience has also shown that this type of grinding wheel structure is more readily and cheaply manufactured in special sizes than other inflated wheels presently on the market because of the lack of special tooling and molds required for any part except the drum. It is, of course, obvious that for a core 7 of a certain size, the dimensions of the drum can be varied only diametrically as the heads 23 and the flanges 24 would remain the same.

What I claim is:

1. In an inflated grinding wheel of the class described comprising: a rigid solid core having a threaded opening formed centrally therethrough and provided on its periphery, at opposite ends, with parallel flat faces, and

provided on its periphery, at each opposite end, with an inwardly directed flange to provide oppositely disposed peripheral grooves, the inner surface of each of said flanges being in alignment and parallel to the axis of said core; an inflatable, flexible drum comprising an annular trough-shaped band having sides inclined inwardly toward each other embracing said core; a head on the end of each of said sides, each of said heads having an outwardly projecting flange for engaging between said core and the inwardly directed flange on said core, said flanges on said head having on their inner and outer surfaces a surface parallel to the axis of said drum.

2. In an inflated grinding wheel of the class described comprising: a rigid solid core having a threaded opening formed centrally therethrough and provided on its periphery, at opposite ends, with parallel flat faces, and provided on its periphery, at each opposite end, with an inwardly directed flange to provide oppositely disposed peripheral grooves, the inner surface of each of said flanges being in alignment and parallel to the axis of said core; an inflatable, flexible drum comprising an annular trough-shaped band having sides inclined inwardly toward each other embracing said core; a head on the end of each of said sides, each of said heads having an outwardly projecting flange for engaging between said core and the inwardly directed flange on said core, said flanges on said head having on their inner and outer surfaces a surface parallel to the axis of said drum; said heads lying in snug engagement with the periphery of said core and the outer surfaces of the flanges on said heads lying snugly in engagement with the inner surfaces of said core; said heads terminating in spaced relation at adjacent sides to provide a passage therebetween.

3. In an inflated grinding wheel of the class described comprising: a rigid solid core having a threaded opening formed centrally therethrough and provided on its periphery, at opposite ends, with parallel flat faces, and provided on its periphery, at each opposite end, with an inwardly directed flange to provide oppositely disposed peripheral grooves, the inner surface of each of said flanges being in alignment and parallel to the axis of said core; an inflatable, flexible drum comprising an annular trough-shaped band having sides inclined inwardly toward each other embracing said core; a head on the end of each of said sides, each of said heads having an outwardly projecting flange for engaging between said core and the inwardly directed flange on said core, said flanges on said head having on their inner and outer surfaces a surface parallel to the axis of said drum;

said heads lying in snug engagement with the periphery of said core and the outer surfaces of the flanges on said heads lying snugly in engagement with the inner surfaces of said core; said heads terminating in spaced relation at adjacent sides to provide a passage therebetween; said core having projecting inwardly from one of its side faces an axially directed passage communicating a radially directed passage with the interior of said drum through the space between the opposed faces of said heads.

5 4. In an inflated grinding wheel of the class described comprising: a rigid solid core having a threaded opening formed centrally therethrough and provided on its periphery, at opposite ends, with parallel flat faces, and provided on its periphery, at each opposite end, with an inwardly directed flange to provide oppositely disposed peripheral grooves, the inner surface of each of said flanges being in alignment and parallel to the axis of said core; an inflatable, flexible drum comprising an annular trough-shaped band having sides inclined inwardly toward each other embracing said core; a head on the end of each of said sides, each of said heads having an outwardly projecting flange for engaging between said core and the inwardly directed flange on said core, said flanges on said head having on their inner and outer surfaces a surface parallel to the axis of said drum; said heads lying in snug engagement with the periphery of said core and the outer surfaces of the flanges on said heads lying snugly in engagement with the inner surfaces of said core; said heads terminating in spaced relation at adjacent sides to provide a passage therebetween; said core having projecting inwardly from one of its side faces an axially directed passage communicating a radially directed passage with the interior of said drum through the space between the opposed faces of said heads; and an air valve mounted in said axially directed passage in said core at the outer end of said passage for permitting the flow of air under pressure therethrough into the interior of said drum and preventing the flow of air under pressure outwardly thereof.
